UNITED STATES PATENT OFFICE.

CHRISTIAN BODRI, OF NEW YORK, N. Y., ASSIGNOR OF ONE-HALF TO HENRY J. KAHRS,
OF NEW YORK, N. Y.

CLOTHES-PIN.

1,274,236.

Specification of Letters Patent. Patented July 30, 1918.

Application filed April 6, 1918. Serial No. 227,044.

To all whom it may concern:

Be it known that I, CHRISTIAN BODRI, a citizen of the United States, and a resident of the city of New York, borough of Bronx, in the county of Bronx and State of New York, have invented a new and Improved Clothes-Pin, of which the following is a full, clear, and exact description.

This invention relates to clothespins and has for an object the provision of an improved structure which will grip a line properly and without injury to the pin even though the line is carrying an appreciable amount of clothes.

Another object is the provision of a clothespin with cuts on each side of the saw-cut for producing resilient gripping tongues.

In the accompanying drawing:

Figure 1 is a side view of a clothespin dis- closing an embodiment of the invention.

Fig. 2 is an edge view of the structure shown in Fig. 1.

Fig. 3 is a view similar to Fig. 1, but showing the pin as applied.

Fig. 4 is a transverse sectional view through Fig. 1 on line 4—4.

Referring to the accompanying drawing by numerals, 1 indicates the usual round body of a clothespin having a round head 2 arranged on one end of the body, while the opposite end merges into the usual side prongs 3 and 4. Between the side prongs 3 and 4 there is provided the usual straight saw-cut 5 merging into the flaring ends 6 and 7. On each side of the straight saw-cut 5 are cuts 8 and 9, which may be straight, as shown in Fig. 1. These cuts result in the production of resilient arms or fingers 10 and 11 which grip the line 12 (Fig. 3) when the pin is in use.

If the line is comparatively large, or the clothes on the line give a comparatively

great diameter the gripping fingers are pressed laterally so as to close up the cuts 8 and 9 at the upper end. The provision of these cuts, and consequently the provision of the fingers 10 and 11 causes the pin to easily accommodate itself to lines of different sizes automatically and to take care of any difference in thickness of clothes without danger of splitting the pin or injuring the clothes. These fingers give an additional gripping action to that provided by the usual resilient effect of the prongs 3 and 4 without requiring any lengthening of the pin. In fact the use of these fingers would permit the shortening of the body 1 as well as the prongs 3 and 4. The gripping action resulting from the use of these fingers will prevent the pin from falling off the line at any time, and will also prevent the clothes from falling off or either being pulled off until the pin has been removed, as any tendency for the clothes to fall off would cause a greater pinching action.

What I claim is:

1. A clothespin comprising a body having a straight saw-cut for part of its length merging into flaring portions, and a straight slot in each side of the saw-cut, said slots intersecting and merging into the saw-cut at the end thereof nearest the head of the pin.

2. A clothespin comprising a round body having a substantially round head, a principal saw-cut at the end opposite the head for receiving a clothesline, and a pair of auxiliary saw-cuts at the sides of said straight saw-cut, said auxiliary saw-cuts being positioned at an angle to the principal saw-cut so as to intersect and merge into the principal saw-cut at the end of the principal saw-cut near said head.

CHRISTIAN BODRI.
